FOREIGN PATENT DOCUMENTS

AU 336372 5/2011

Primary Examiner — Kevin Rudzinski(74) *Attorney, Agent, or Firm* — Hamre, Schumann, Mueller & Larson, P.C.**(57) CLAIM**

The ornamental design for a lighting apparatus, as shown and described.

DESCRIPTION

FIG. 1 is a top perspective view of a lighting apparatus. FIG. 2 is another top perspective view of the lighting apparatus.

FIG. 3 is a bottom perspective view of the lighting apparatus.

FIG. 4 is top plan view thereof.

FIG. 5 is a bottom plan view thereof.

FIG. 6 is a front side elevational view thereof. The rear side elevational view is identical; and,

FIG. 7 is a right side elevational view thereof. The left side elevational view is identical.

The broken lines illustrating portions of the lighting apparatus form no part of the claimed design.
